UNITED STATES PATENT OFFICE.

FRED TENNEY, OF DONCASTER, ENGLAND.

GAME.

1,393,408.

Specification of Letters Patent. Patented Oct. 11, 1921.

Application filed October 23, 1919. Serial No. 332,791.

To all whom it may concern:

Be it known that I, FRED TENNEY, of 26 Buckingham road, Doncaster, England, have invented new and useful Improvements in Games; and I do hereby declare the following to be a full, clear, and exact description of the same.

The present invention has for object to provide a game suitable for either indoor, 10 or outdoor, use, and for children, or adult, players, which will provide considerable amusement while at the same time calling for the exercise of skill, judgment, and quickness.

15 The game apparatus according to my invention comprises a barrier adapted to be placed between the players of opposite sides, and formed, or provided, with a single aperture, and the main idea of the game is to exchange a shuttlecock or similar object between the opposing sides of players by driving it through the aperture, instead of over a net as in lawn tennis, badminton, and other games. The game may be played under rules similar to those in use for lawn 25 tennis, or badminton, but according to the preferred form of the game it is played with a feathered, or like, shuttlecock device, somewhat similar to an ordinary 30 shuttlecock, but possessing much greater resiliency, so that it can be kept in play after striking the ground, or the table, upon which it is played. An improved shuttlecock device of this kind forms the subject 35 matter of my concurrent application for Letters Patent, Serial No. 332,790, filed Oct. 23, 1919.

In order to render the aperture clearly visible to the players and at the same time 40 to enable them to see the movements of their opponents, part of the barrier surrounding the aperture is preferably formed by a white transparent material, as linen gauze, and in order to adapt the apparatus to suit players 45 of different degrees of skill, the size of the aperture is preferably adapted to be adjusted according to requirements.

According to another feature of the invention the height of the aperture above the 50 ground, or table, is also adjustable to suit players of different heights, or to introduce

further difficulty into the game. By this means one apparatus may be adapted for the use of adults or children as required.

The apparatus according to my invention 55 may be constructed in various sizes, but preferably for use as an indoor game it is constructed of a size suitable for mounting on a table, and for use as an outdoor game it is constructed of a size suitable for a small 60 lawn. In the following description various examples of apparatus for indoor use are described, but it will readily be obvious how such examples may be adapted for outdoor 65 use.

Further features of the invention will hereinafter appear from the claims, and from the following description of the accompanying drawings, which illustrate various examples of apparatus embodying my 70 invention.

In the accompanying drawings:—

Figure 1 is a perspective view of one form of apparatus mounted for use on a table.

Fig. 2 is an elevation of a second form of apparatus.

Fig. 3 is a sectional view of one of the uprights of the apparatus shown in Fig. 2.

Fig. 4 is an elevation of a third form of apparatus.

Fig. 5 is an elevation, partially in section, of a fourth form of apparatus.

Fig. 6 is an elevation of a fifth form of apparatus.

Fig. 7 shows the preferred form of shuttlecock, for use with the apparatus.

Figs. 8 to 12 inclusive are views to an enlarged scale of certain details of the apparatus.

Fig. 13 is an elevation illustrating an alternative means for varying the effective size of a hoop-shaped aperture frame.

Fig. 14 is an elevation of the upper part of a sixth form of apparatus, and

Fig. 15 is an elevation of a modified form of a rectangular aperture frame provided with means for varying its size in both directions.

Referring to Fig. 1, the apparatus, which 100 is shown mounted on a table in position for play, comprises two uprights 1 formed with

hooks or eyes 34 in any suitable manner. Additional central support is provided by suitable hooks and eyes attached to the lower bar of the frame and to the upper edge of 5 the screen respectively.

The provision of the hinges in the frame, and for the legs of this apparatus, enable it to be folded up into a comparatively small space as will be readily understood.

- 10 Referring to Fig. 5 the apparatus shown therein comprises a plain hoop 35 connected by a suitable joint member 36 with a rod 37 adapted to slide in a tubular standard 38 provided with three supporting legs 39. 15 The hoop may be fixed at any desired height by means of the clamping screw 40 provided in the tubular standard 38, and adapted to grip the rod 37. The hoop is preferably painted white, and if desired the 20 supporting legs 39 may be made collapsible after the manner of the legs of music supporting stands.

Referring to Fig. 6, the apparatus shown therein comprises a plain white hoop 41, supported by rods 42 pivoted intermediate of their length to each other at 43. The hoop is secured to the rods 42 by means of clamping members 44, shown in detail in Fig. 11. The hoop passes through the hole 45 and can be clamped by means of the thumb screw 46, while the rod 42 passes through the hole 47 and the clamping member 44 can be secured at any desired point thereon by means of the thumb screw 48, the 35 head of which is preferably formed as an eye to which the supporting stays 9 are adapted to be secured.

The lower ends of the rods are provided with a brace member 49 pivoted at one end 40 to a rod 42 at 50, and adapted to pass at the other end through a slot provided on the other rod 42. The slot is preferably formed by a metal bridge piece 51 secured to the rod, and provided with a clamping 45 screw 52.

It will be clear that the brace member 49 may be clamped by the screw 52 at any desired point of its length, so enabling the distance between the upper parts of the rods 50 42 to be varied, whereby the height of the hoop above the ground may be adjusted to meet requirements. The sliding clamping members 44 enable the hoop to be fixed securely to the rods 42 in any of the various 55 positions that may be assumed by the rods 42.

The provision of the brace member 49 takes off much of the strain from the hoop when the stays 9 are tightened up, and 60 thereby prevents the hoop from being pulled out of shape.

The hoop members used in any of the forms of apparatus hereinbefore described may be made adjustable in size in the manner illustrated by Fig. 9. The hoop is

formed by a thin flexible strip, or lath, of wood, metal, or other suitable material adapted to be bent into circular shape and to have its ends secured in any desired position in relation to each other by means of 70 clamping members 53, which may be permanently secured to the respective ends of the strip, or not, as desired.

In Fig. 10 is illustrated an alternative method of forming a hoop of adjustable 75 size. According to this construction the hoop is formed by a flexible tubular, or partially tubular, lath 57 of metal, or other suitable material, one end of which is adapted to fit into and slide within the opposite 80 end, a clamping screw 58 being provided to clamp the inner member at any desired position within the outer member.

The preferred form of shuttlecock, according to my concurrent application for 85 Letters Patent, Serial No. 332,790, filed Oct. 23, 1919 for use in connection with the game is illustrated by Fig. 7. It comprises a base 54 to the upper surface of which is secured a retarding, or steadyng device formed by 90 the cone of feathers 55, and to the lower surface of which is detachably secured a highly resilient member, formed for example by a pneumatic india rubber ball 56.

Fig. 13 of the drawings illustrates an 95 alternative method whereby the effective playing aperture of a hoop member such as shown in Figs. 1, 5 and 6, may be adjusted to suit players of different degrees of skill, or to increase or decrease the difficulty of 100 the game. According to this construction the hoop member is provided with a plurality of eyes or hooks 57 disposed at equal distances around its circumference, and a white cord or tape is adapted to be threaded 105 through the eyes to produce playing apertures of various sizes and shapes in the manner indicated in the drawings by the dotted lines. By threading the tape through all of the eyes a playing aperture 110 only slightly smaller than the full size of the hoop is produced, while by employing only four of the eyes or hooks the smallest aperture is produced, such aperture being rectangular in shape and disposed with its 115 length vertically or horizontally as may be desired. Obviously any number of eyes may be provided on the hoop to give any desired range of adjustment for the size of the aperture.

Referring to Fig. 14 of the drawings the construction of apparatus shown therein comprises a pair of standards 58 which may be supported in a vertical position in any suitable manner. Slidably mounted on 125 these standards by means of the sliding screw clamps 59 is the rectangular or square aperture frame 60, the sides of which may be provided with eyes or hooks 57 for use in forming playing apertures of different 130

shapes and sizes in a manner similar to that described with reference to Fig. 13. Instead of defining the edge of the playing aperture by means of a white cord or tape there may be provided a number of borders of varying widths—preferably of gauze or the like—and inclosing openings of various shapes or sizes. Any selected border may then be attached by hooks and eyes, or by lacing, to the aperture frame 60. The frame 60 is made collapsible by providing it at two opposite corners with pivot pins 61, and at the other two opposite corners with joint pins and winged nuts 62. In order to fold the apparatus up into a convenient space when not required for use it is then only necessary to remove the winged nuts and joint pins 62, to enable the upper and lower bars of the frame 20 to be revolved about their pivots 61 until they come into alignment with the side bars of the frame to which they are pivoted.

According to the modified construction of rectangular aperture frame illustrated by Fig. 15, one or both pairs of opposite sides of the frame are adapted to have their lengths varied to produce apertures of different sizes. For this purpose each side so adapted is divided into two parts 64 each of which is provided with a longitudinal slot 65. Each part 64 is also provided at its end with a bolt 66 having a winged nut 67, and engaged in the slot of the adjacent part 64. The two parts 64 may thus be adjusted longitudinally in relation to each other and may be clamped together in any desired position by means of the two winged nuts 67. It will be clear that by this means the frame may be adjusted to any desired size within the limits formed by the ends of the slots 65. The frame may be mounted on standards in a manner similar to that described with reference to and as illustrated by Fig. 14.

45 While I have hereinbefore described several different constructions of apparatus according to my invention I wish it to be understood that my invention also includes many other constructions which may be devised within the scope of the claims hereinafter set out.

What I claim is:—

1. A game apparatus comprising a barrier adapted to be set up between players of opposing sides, a single aperture in said barrier, means whereby the size of said aperture may be varied as desired, and a shuttlecock device adapted to be exchanged between the opposing sides of players through said aperture.

2. A game apparatus comprising a barrier adapted to be set up between players of opposing sides, a single aperture in said barrier, means whereby the height of said aperture may be varied as desired, and a

shuttlecock device adapted to be exchanged between the opposing sides of players through said aperture.

3. A game apparatus comprising a barrier adapted to be set up between players of opposing sides, a single aperture in said barrier, means whereby the size of said aperture may be varied as desired, means whereby the height of said aperture may be varied as desired, and a shuttlecock device adapted to be exchanged between the opposing sides of players through said aperture.

4. A game apparatus comprising a barrier adapted to be set up between players of opposing sides, a single aperture in said barrier, a frame surrounding said aperture parts of the periphery of said frame being relatively movable to vary the size of the aperture, and a shuttlecock device adapted to be exchanged between the opposing sides of players through said aperture.

5. A game apparatus comprising a barrier adapted to be set up between players of opposing sides, a single aperture in said barrier, a frame surrounding said aperture, means adapted to support said frame in a vertical position at any desired height, and a shuttlecock device adapted to be exchanged between the opposing sides of players through said aperture.

6. A game apparatus comprising a barrier adapted to be set up between players of opposing sides, a single aperture in said barrier, a frame surrounding said aperture, means for varying the length of the periphery of said frame, means adapted to support said frame in a vertical position at any desired height, and a shuttlecock device adapted to be exchanged between the opposing sides of players through said aperture.

7. A game apparatus comprising a pair of standards, means for supporting said standards in a vertical position, a cross bar connecting the tops of said standards, a second cross bar connecting said standards below the first mentioned cross bar, and means for adjusting the vertical position of the second cross bar on said standards.

8. A game apparatus comprising a pair of standards each of said standards being formed in two parts longitudinally adjustable in relation to each other, means for securing said parts in different longitudinal relations to each other, means for supporting the two lower parts of each standard in vertical position, a cross bar connecting the tops of the upper parts of said standards, and a second cross bar connecting the said upper parts below the first mentioned cross bar.

9. A game apparatus comprising a pair of standards each of said standards being formed in two parts longitudinally adjustable in relation to each other, means for se-

curing said parts in different longitudinal relations to each other, means for supporting the two lower parts of each standard in vertical position, a cross bar connecting the 5 tops of the upper parts of said standards, a second cross bar connecting the said upper parts below the first mentioned cross bar, and means for adjusting the vertical posi-

tion of each of said cross bars in relation to the upper parts of said standards. 10

In testimony whereof I affix my signature in presence of two witnesses.

FRED TENNEY.
